BOTTLE OR SIMILAR ARTICLE

Victor Koenigsberg, Franklin Square, N.Y., assignor to Colgate-Palmolive Company, New York, N.Y., a corporation of Delaware

Filed Oct. 21, 1964, Ser. No. 82,266

Term of patent 14 years

(Cl. D58—8)

FIG. 1

FIG. 4

Des. 205,422

FIG. 1 is a side elevational view of a bottle or similar article embodying my new design;

FIG. 2 is an end elevational view;

FIG. 3 is a top plan view; and

FIG. 4 is a bottom plan view thereof.

The side and end not shown are the same in appearance as the side and end shown.

The dominant features of my design reside in the portion shown in full lines.

I claim:

The ornamental design for a bottle or similar article, as shown and described.
